UNITED STATES PATENT OFFICE.

HENRY H. FEFEL, OF NEW YORK, N. Y., ASSIGNOR TO THE MULTIPLE POWER COMPANY, OF WEST VIRGINIA.

DESIGN FOR A BICYCLE-FRAME.

SPECIFICATION forming part of Design No. 28,991, dated July 5, 1898.

Application filed May 7, 1898. Serial No. 680,071. Term of patent 14 years.

To all whom it may concern:

Be it known that I, HENRY H. FEFEL, a citizen of the United States, residing in New York, in the county of New York and State of New York, have invented and produced a new and original Design for Bicycle-Frames, of which the following is a specification, reference being had to the accompanying drawing, forming a part thereof.

- The figure in the accompanying drawing is a perspective view of a bicycle-frame, showing my new design.

Broadly speaking, the frame presents the appearance of a right-angled triangle cut off near its apex and made up of four principal parts or elements A, B, C, and D, two of which are bifurcated or forked.

- The rod or tube A, which is of uniform size and shape throughout its length, is joined with the head B near one of the extremities thereof. A tube C is joined to said head B near its other or lower extremity, the angle between A and B being somewhat greater than forty-five degrees and the angle between B and C being more nearly a right angle. At a suitable distance from the head B the tube C is divided or forked, the two branches or

tines c c thereof extending in the same general direction as C, but diverging slightly with respect to each other. The outer end of each branch or tine c c merges into a rather wide flat bracket or extension c', the two brackets or extensions being parallel with each other and substantially parallel with the tube A.

D is a tube or post joined to the tube A in such manner as to form a right angle therewith. At a suitable distance from the point of connection this tube or post is divided or forked similarly to tube C and the two branches or tines d d thereof joined with the brackets or extensions c' c' near the point of juncture of the tube C, thus leaving a considerable portion of said brackets or extensions projecting beyond the tines d d.

I claim—

The design for a bicycle-frame substantially as herein shown and described.

In witness whereof I subscribe my signature in presence of two witnesses.

HENRY H. FEFEL.
